UNITED STATES PATENT OFFICE

WILLIAM C. CORYELL, OF YOUNGSTOWN, OHIO

METAL LATH SLITTING PRESS

Application filed April 20, 1929. Serial No. 356,784.

This invention relates to improvements in metal lath slitting punch presses of the type in which a continuously rotating power shaft is designed to produce intermittent rotary motion of feed rollers employed to deliver sheets to be slit by the slitting elements of the press. The object of the present improvements is to provide a novel arrangement of levers for transmitting motion from the power shaft to the feed rollers whereby, with minimum power applied to the power shaft and at any given rate of speed thereof, maximum feeding movement of the rollers with ample force to accomplish their function may be obtained, thus to secure maximum production in a minimum amount of time and with the consumption of minimum energy.

With the foregoing general purpose in view, the invention consists in the novel features of construction, combination and arrangement of parts as will be hereinafter more fully described, illustrated in the accompanying drawings and defined in the appended claims.

In the drawings, wherein like characters of reference denote corresponding parts in the different views:

Figure 1 is a side elevation of a metal lath slitting press having the present improvements in one preferred form embodied therein.

Fig. 2 is a front elevation of the press.

Fig. 3 is a side elevation showing the levers in a different position from the position they occupy in Fig. 1; and

Fig. 4 is a view partly in elevation and partly in section of the levers shown in Fig. 3.

Referring to the drawings in detail, A designates generally a metal lath slitting press of conventional design, including in its organization a frame 10, a power shaft 11 and feed rollers 12. In accordance with common practice, the power shaft 11 is disposed horizontally and mounted in suitable bearings in frame 10 near the upper end thereof for continuous rotation in any suitable or desired manner as, for example, by means of a suitably driven endless steel belt 13 trained over a fly-wheel 14 fixed to said shaft at one side of frame 10, while feed

rollers 12 are mounted on shafts 15 journaled in the frame near the lower end thereof, one pair of said rolls being disposed at the front and another pair at the rear of the press. Endless steel belts are preferably used because the drive is vertical, and the shafts of the motor and the press are arranged on short centers, both of these features being difficult for other belting than steel belts, but comparatively easy for the latter.

Feed rollers 12 are adapted to be rotated intermittently by power derived from the continuously rotating power shaft 11 and to this end, in accordance with the present invention, a driving connection, designated generally at B and including essentially a plurality of cooperating levers, is provided between said shaft 11 and said rollers 12 whereby this purpose is accomplished.

In detail, connection B is inclusive of a pair of levers 16 and 17, the former of which is pivoted intermediate its ends as at 18 to the frame 10 and the latter of which is of the three-arm or of inverted T-shape type and also is pivoted to said frame, at the junction of its arms, as indicated at 19.

One feed roll shaft 15 of each pair of such shafts has fixed thereto a ratchet wheel 20, the shafts of each pair being operatively connected together by pinions 21, and the two lower, substantially aligned arms 22, 22 of the lever 17 are provided with spring pressed pawls 23, 23, respectively, cooperating with said ratchet wheels, respectively, whereby oscillation of said lever 16 is effective to produce intermittent rotation of the respective pairs of feed rolls to effect step-by-step feed of a sheet of material to be slit, through the press.

The upper end of the intermediate arm 24 of lever 17 is operatively connected with the lower arm of the lever 16, said connection being effected by slotting one of said arms, the arm of lever 16 in this instance, as indicated at 25, mounting a block 26 in said slot for sliding movement and journaling a pin 27 carried by the other arm, in this instance the arm 24, in said block.

The end of the shaft 11 opposite to the end thereof on which the fly-wheel 14 is mounted,

is provided with a crank pin 28 journaled in a block 29 slidably mounted in a slot 30 formed in the upper end of the upper arm of lever 16. Thus, when shaft 11 is 5 rotated, the lever 16 is rocked on its pivot 18 and the lever 17 as a consequence is rocked or oscillated on its pivot 19 causing the feed rollers to be intermittently rotated.

If desired, the pivot 18 may be rendered 10 adjustable in any suitable manner so that the effective length of the respective arms of lever 16 may be varied, the slots 25-30 permitting said lever to be raised or lowered. In any event it is manifest, due to the provision and 15 to the general arrangement of the parts of the mechanism as shown and described, that a crank pin 28 having a relatively small throw is effective to produce relatively extensive arcuate movements of the pawls 23, so 20 that for a given rate of rotation of power shaft 11, and by minimum power delivered to said shaft, maximum feed movements of the feed rollers with ample force for all ordinary feeding purposes may be obtained.

Obviously, by varying the effective lengths 25 of the respective lever arms and the throw of crank 28, practically any desired feed of the sheet between the feed rollers may be obtained. Moreover, the present driving connection 30 between the power shaft and the feed rollers is relatively cheap and easy to produce, durable, efficient in its purpose and capable of incorporation in presses of present designs substantially without alterations 35 thereto.

Without further description it is thought 40 that the features and advantages of the invention will be readily apparent to those skilled in the art, and it will of course be understood that changes in the form, proportion and minor details of construction may be resorted to, without departing from the spirit of the invention and scope of the appended claims.

45 I claim:

1. In a metal lath slitting press, feed rolls, a power shaft inclusive of a crank element, an intermediately pivoted lever operatively connected at one end with said crank element 50 whereby continuous rotation of said shaft oscillates said lever, a second intermediately pivoted lever operatively connected with said first lever whereby both levers are oscillated in unison, and pawl and ratchet connecting means between said second lever and said feed rolls.

2. In a metal lath slitting press, a pair of spaced feed rollers, a T-shaped three arm lever between said rolls, said lever being pivoted 60 at the junction of its arms, a pawl and ratchet connection between one arm of said lever and one of said feed rollers and another pawl and ratchet connection between a second arm of said lever and the other feed roller, whereby oscillation of said lever imparts intermit-

tent rotation to said feed rollers, a rotatable power shaft, a second lever pivoted intermediately and operatively connected at one end with said power shaft whereby continuous rotation of the latter oscillates said second mentioned lever, and a connection between the other end of said second mentioned lever and the third arm of said first mentioned lever whereby oscillation of said second mentioned lever oscillates said first mentioned lever.

In testimony whereof I hereunto affix my signature.

WILLIAM C. CORYELL.
